Primary Examiner — Mitchell Siegel(74) Attorney, Agent, or Firm — Rebecca Hanovice; Michael Catania; Sonia LariCLAIM

The ornamental design for a golf club head, as shown and described.

DESCRIPTION

FIG. 1 is a top perspective view of a golf club head; FIG. 2 is a rear elevation view of the golf club head of FIG. 1;

FIG. 3 is a front elevation view of a golf club head of FIG. 1;

FIG. 4 is a heel-side elevation view of a golf club head of FIG. 1;

FIG. 5 is a toe-side elevation view of a golf club head of FIG. 1;

FIG. 6 is a top plan view of the golf club head of FIG. 1; and, FIG. 7 is a bottom plan view of the golf club head of FIG. 1.

The broken lines in the drawings are included for the purpose of illustration and form no part of the claimed design.
